UNITED STATES PATENT OFFICE.

ROY W. BROUHARD AND WILLIAM H. DONALDSON, OF COLO, IOWA.

VALVE-PULLER.

1,381,890.

Specification of Letters Patent. Patented June 14, 1921.

Application filed July 6, 1920. Serial No. 394,314.

To all whom it may concern:

Be it known that we, ROY W. BROUHARD and WILLIAM H. DONALDSON, citizens of the United States, and residents of Colo, in the 5 county of Story and State of Iowa, have invented a certain new and useful Valve-Puller, of which the following is a specification.

The object of our invention is to provide 10 a valve pulling tool particularly adapted for use with motors of the over head type.

With this and other objects in view our invention consists in the construction, arrangement and combination of the various 15 parts of the device, whereby the objects contemplated are attained, as hereinafter more fully set forth, pointed out in our claims and illustrated in the accompanying drawings, in which:

20 Figure 1 shows an elevation of a valve pulling tool embodying our invention.

Fig. 2 shows a similar view illustrating the use of the tool when installed on the washer on a valve stem.

25 Fig. 3 shows a view similar to that of Fig. 2, illustrating the placing of the tool on the washer.

Fig. 4 shows a detail view of a slightly modified form of our invention.

30 With certain kinds of internal combustion engines used on automobiles, there are provided valves for controlling the fuel inlet and the exhaust gas outlet, which valves may have stems such as that indicated by the 35 reference numeral 10 in the drawing.

At the upper end of the stem 10 is a washer or the like 11, below which is a spring 12 by 40 which the valve is held normally seated, which frequently becomes necessary to remove the valve for cleaning or grinding the valve or valve seat, and this is sometimes a difficult matter especially where the valve is stuck.

Ordinarily the first movement of the removal or raising against the pressure of the 45 spring 12, is accomplished by inserting some instrument under the edge of the washer 11 and prying upwardly. If the spring is very strong or if the valve is stuck this prying 50 operation is likely to result in bending the valve stem or otherwise injuring the parts.

The tool described herein is especially adapted for raising such valves without injury thereto, without waste of time.

55 It may be mentioned in this connection

that the removal of the valves is often a very slow process on account of the great care which is required.

With the tool under consideration the removal of the valve is a quick and easy process. 60 The tool shown herein, comprises a shank 13, having a removable head 14^a, and the other end of the shank 13 has divergent, resilient arms 14, which terminate inwardly extending opposite engaging fingers 15, the 65 upper surfaces of which are substantially flat and the lower surfaces of which are beveled as at 16.

In the practical use of the tool shown 70 herein the fingers 15 are slid under the washer 11 from the side, or if this is difficult to do on account of the proximity of a part of the engine, the tool may be placed in proper position by first placing it in the position shown in Fig. 3, with one finger 15 below the washer 11, and with the other finger 15 just above the washer 11 and diametrically opposite from the first finger. The shank 13 is then swung from its inclined position shown in Fig. 3 toward vertical position 75 illustrated by lines in Fig. 3, whereupon one of the arms 14 will be sprung laterally until the upper finger 15 clears the washer 11 whereupon the resiliency of the arms 14 will cause the last mentioned finger 80 85 15 to spring to position beneath the washer 11.

There is loosely mounted on the shank 13 a tube 17 illustrated in Figs. 1 and 2 which serves as a hammer. After the tool has been installed in the position shown in Fig. 2 it 90 may be grasped at the lower portion by one hand and the tube 17 may be raised with a sharp blow against the head 14^a and it will be seen that if the valve is stuck it will be jerked loose from its seated position with a 95 movement which will cause no injury to the stem.

If the valve is not stuck the tool may be raised with a steady upward pull. The advantages of such a tool will be largely seen 100 from the foregoing description. It is a very simple and inexpensive construction and may be quickly and easily installed in position for use and will save a great deal of time moving the valves to position where 105 they are accessible. It makes it possible to loosen the valve which has been stuck without injury to the valve and to do so almost instantaneously.

In Fig. 4 we have shown a modified form 110

of our tool in which the shank 13 is provided with three equidistantly spaced arms 14 instead of two.

Some changes might be made in the construction and arrangement of the tool shown herein without departing from the real purpose and spirit of the invention sought to be covered by this application and it is our purpose to cover by the claim of the application 10 any modification in structure or use of mechanical equivalents which may be reasonably included within their scope.

We claim as our invention:

1. A tool of the kind described having a shank, a head on said shank, divergent resilient arms on said shank, terminating in inwardly inclined fingers, and a hammer member slidably mounted on said shank.

2. In a tool of the class described a shank 20 having at one end diverging resilient arms, terminating in opposite inwardly extending fingers, having flat surfaces arranged substantially horizontal on the upper side when

the shank is upright, and having beveled surfaces on their lower side.

3. In a tool of the class described a shank having at one end diverging resilient arms, terminating in opposite inwardly extending fingers, having flat surfaces arranged substantially horizontal when the shank is upright, on the upper side and having beveled surfaces on their lower sides, said tool having a detachable head and a hammer member slidably mounted on said shank.

4. In a tool of the class described a shank 35 having at one end diverging resilient arms, terminating in opposite inwardly extending fingers, having flat surfaces arranged substantially horizontal when the shank is upright, on the upper side and having beveled 40 surfaces on their lower sides, said tool having a head, and a slideable hammer member mounted on said shank.

Des Moines, Iowa, June 3, 1920.

ROY W. BROUHARD.

WILLIAM H. DONALDSON.
